UNITED STATES PATENT OFFICE.

MONTGOMERY H. WATSON, OF DAYTON, OHIO.

ENVELOPE.

SPECIFICATION forming part of Letters Patent No. 276,314, dated April 24, 1883.

Application filed November 9, 1882. (Model.)

To all whom it may concern:

Be it known that I, MONTGOMERY H. WATSON, a citizen of the United States, residing at Dayton, in the county of Montgomery and State of Ohio, have invented a certain new and useful Improvement in Envelopes; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to improvements in envelopes known as the "bellows" envelope, used for filing legal and other papers; and it consists of like top and bottom pieces of paper having rims or flaps on three sides, which are united by a textile or other suitable fabric which is glued or pasted to said flaps, thus forming an envelope whose top and bottom sides may be in contact, and expanding with the proportions of the contents.

The construction of the envelope is illustrated by the accompanying drawings, in which—

Figure 1 is an oblique view of the improved envelope. Fig. 2 is the form of the top and bottom sheet or blank of the same. Fig. 3 is an enlarged transverse section of the same.

Similar letters refer to similar parts throughout the several views.

B represents the blank as it is cut out of suitable paper, Fig. 2, and has a semicircular notch in the right end, and the corners at the left end are clipped, and the edges are creased for folding, as indicated by dotted lines at D. Two blanks are placed on a quadrangular block, the edges are bent down upon the same, and the muslin strip C is glued or pasted onto these edges or flaps T. The strip may be of any textile or other suitable material, and is made to adhere to the flaps on three sides of the envelope. For purposes of commerce, the top and bottom are pressed snugly down on the flexible sides, and in use they expand with the proportions of their contents.

Having fully explained my invention, what I claim, and desire to secure by Letters Patent, is—

An envelope formed of two identical blanks having folded side and end portions, T, united by a suitable flexible strip, C, substantially as shown and described.

In testimony that I claim the foregoing as my own I affix my signature in presence of two witnesses.

MONTGOMERY H. WATSON.
